FIG.4

FIG.6

FIG.5

Fig. 1 is a front elevational view of an eye protective industrial spectacle frame front embodying my new design;

Fig. 2 is a top plan view of the same;

Fig. 3 is a rear elevational view thereof;

Fig. 4 is a bottom plan view;

Fig. 5 is a central vertical sectional view on line 5—5 in Fig. 1; and

Fig. 6 is a cross-sectional view thereof taken on the line 6—6 of Fig. 3.

The characteristic features of my design for the eye

protective industrial spectacle frame front disclosed reside in the bridge and in the frame portions adjacent thereto having the configurations shown.

I claim:

The ornamental design for an eye protective industrial spectacle frame front, substantially as shown and described.
